ATTORNEY

UNITED STATES PATENT OFFICE.

JOHN R. HAMPEL, OF MILWAUKEE, WISCONSIN.

DESIGN FOR LEATHER.

60,237.

Specification for Design.

Patented Jan. 17, 1922.

Application filed August 4, 1921. Serial No. 489,887. Term of patent 14 years.

To all whom it may concern:

Be it known that JOHN R. HAMPEL, a citizen of the United States, residing at Milwaukee, in the county of Milwaukee and State of Wisconsin, has invented a new, original, and ornamental Design for Leather, of which the following is a specification, reference being had to the accompanying drawing, forming a part hereof.

The drawing is a plan view of a piece of leather embodying my new design.

I claim:

The ornamental design for leather as herein shown.

JOHN R. HAMPEL.
